US00D971340S

(12) **United States Design Patent** (10) **Patent No.:** **US D971,340 S**
Wang (45) **Date of Patent:** **** Nov. 29, 2022**

(54) **SELF BALANCING SCOOTER**

(71) Applicant: **Shenzhen cloud access information technical service Co., Ltd**, Shenzhen (CN)

(72) Inventor: **Xiao Wang**, Qingdao (CN)

(***) Term: **15 Years**

(21) Appl. No.: **29/785,228**

(22) Filed: **May 24, 2021**

(51) LOC (13) Cl. **21-01**

(52) U.S. Cl.

USPC **D21/423**

(58) **Field of Classification Search**

(57) **CLAIM**

The ornamental design for a self balancing scooter, as shown and described.

DESCRIPTION

FIG. 1 is a perspective view of a self balancing scooter showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines showing of the self balancing scooter is for the purpose of illustrating portions of the article and forms no part of the claimed design.

1 Claim, 7 Drawing Sheets
